US00D959166S

(12) **United States Design Patent** (10) **Patent No.:** **US D959,166 S**
(45) **Date of Patent:** **** Aug. 2, 2022**

(54) **FLOWER HOLDER**

(71) Applicant: **Ningbo Evergreen Garden Tools Co., Ltd.**, Ningbo (CN)

(72) Inventor: **Shengyin Zhao**, Cixi (CN)

(73) Assignee: **Ningbo Evergreen Garden Tools Co., Ltd.**, Ningbo (CN)

(**) Term: **15 Years**

(21) Appl. No.: **29/802,072**

(22) Filed: **Aug. 3, 2021**

(51) LOC (13) Cl. **06-04**

(52) U.S. Cl.

USPC **D6/405**; D11/155

(58) **Field of Classification Search**

USPC D11/143, 148, 152; D6/403, 404, 405;

D8/1

CPC A01G 9/12; A01G 9/124; A01G 9/126;

A01G 9/128

See application file for complete search history.

(57) **CLAIM**

The ornamental design for a flower holder, as shown and described.

DESCRIPTION

FIG. 1 is a perspective view of a flower holder, showing my new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
